UNITED STATES PATENT OFFICE.

GEORGE ROSS, OF NEWPORT, KENTUCKY.

IMPROVEMENT IN BLACKWASHING MOLDS.

Specification forming part of Letters Patent No. 42,600, dated May 3, 1864.

To all whom it may concern:

Be it known that I, GEORGE ROSS, of Newport, in the county of Campbell and State of Kentucky, have invented a new and useful Improvement in Blackwashing Pipe-Molds; and I do hereby declare that the following is a full, clear, and exact description of the same, reference being had to the accompanying drawings, forming part of this specification, in which—

Figure 1 represents a vertical central section of my invention when charged and ready for use. Fig. 2 is a similar section of the same, showing its application to a mold. Fig. 3 is a transverse section of the sprinkler. Fig. 4 is a transverse section of the fender.

Similar letters of reference in the several views indicate corresponding parts.

This invention consists in the employment or use of a casing fitting nicely over the sprinkler and arranged in such a manner that when the casing covers the sprinkler the latter can be filled with blackwash, and nothing is allowed to escape, and after the sprinkler has been adjusted in the proper position over the center of the mold said casing can be readily removed. The application of the blackwash to the inside of the mold can thus be effected in a short time with little trouble and without danger of injuring the interior of the mold.

The invention consists, also, in the combination, with the sprinkler, of a conical guide piece or head in such a manner that the sprinkler is retained in the center of the mold and prevented from damaging its sides.

The invention consists, finally, in a fender placed under the mold into a suitable tank and used, in combination with the sprinkler, in such a manner that said sprinkler, after having passed through the mold, is still kept in the center and prevented from floating off to any other part of the tank, whence it cannot conveniently be fetched out.

To enable others skilled in the art to make and use my invention, I will proceed to describe it.

A represents the sprinkler, which is made of tinned sheet-iron or other suitable material in the form of a cylinder, and provided with a series of perforations, *a*, through which the blackwash is intended to ooze out. The diam-

eter of this sprinkler is somewhat smaller than the inside diameter of the pipe-mold to which the blackwash is to be applied, and it is provided with a conical guide piece or head, B, intended to keep it in the center of the mold and to allow it to pass down through said mold without injury to its sides. The sprinkler is suspended from a rope, C, which is secured in a ring, *b*, at the upper end of a rod, *c*, that passes down through the cylindrical body of the sprinkler and is firmly inserted into the head B.

D is a casing made of tinned sheet-iron or other suitable material, and provided with a flange, *d*, at its bottom. This casing fits nicely over the sprinkler A, and when it is placed on said sprinkler the flange *d* projects beyond the edge or shoulder of the head B. When the sprinkler is filled with blackwash and the casing covers up the perforations *a*, nothing is allowed to escape from the interior of the sprinkler, and thus arranged it can be carried to any place and adjusted over the mold in the desired position. The mold E is formed in a flask, F, which stands in a perpendicular position in a pit and over a tank, G, intended to receive the surplus blackwash placed directly under the mold, and in the tank G is the fender H, which forms the guide for the sprinkler, after the same has passed through the mold, and prevents it floating off sidewise. The top of the flask is covered by a board, I, with a flange to keep it in place, and provided with a hole in its center just large enough to let the head of the sprinkler pass, but too small for the flange of the casing D. After the sprinkler has been charged with blackwash it is brought over the hole in the board I and lowered. As soon as the flange of the casing D comes in contact with the board I, it begins to lift off, and the blackwash oozes out through the perforations *a* and is applied uniformly to the interior of the mold.

With ordinary devices for blackwashing pipe-molds the sprinkler is placed into the mold, and then the wash is poured in. It is obvious that by these means the blackwash cannot be equally distributed; and, furthermore, if some of it is spilled in pouring it into the sprinkler, the interior of the mold is liable to be damaged. These difficulties are obviated by my invention, which allows of carrying the blackwash in the sprinkler to the mold.

and of distributing it uniformly throughout. The surplus wash collects in the tank G, and by the fender H the sprinkler is held in the center and prevented from floating off on one side, which would render the recovery of the same troublesome and inconvenient.

What I claim as new, and desire to secure by Letters Patent, is—

1. The flanged casing D, in combination with the sprinkler A, constructed and operating substantially as and for the purpose shown and described.

2. The combination of the board I with the

casing D and sprinkler A, substantially as and for the purpose set forth.

3. The head B, in combination with the sprinkler A and casing D, as set forth.

4. The employment or use of the fender H, in combination with the sprinkler A and casing D, constructed and operating in the manner and for the purpose substantially as specified.

GEORGE ROSS.
